BEARING PLAY REMOVER

Thomas E. Hayes, Washington, D. C.

Application April 12, 1949, Serial No. 87,042

1 Claim. (Cl. 308—65)

1

This invention relates to bearing play-removing devices, and more particularly to such devices for preventing lost motion due to bearing misfit in pivoted members used in precision control devices.

Many devices are controlled by precision means which moves but an imperceptible amount to complete its full operative stroke. Many of these control units are in the form of a pivoted lever, the lever being used to operate a switch, or in some other way control the operation of the machine. Where the control lever also forms part of a caliper mechanism, it is extremely important that the movement of the lever be in exact relation to the thickness of the material causing the movement, and any play between the lever and its pivot pin will result in inaccuracies of control.

One example of such a device is the mechanism employed in currency counting and sorting machines, such as disclosed in Patent No. 2,429,159. In this type of machine, paper bills are inserted between various roller pairs for counting, and the thickness of the paper bill actuates the control device for instituting the counting operation. The same control device will operate to stop the machine when two bills are inadvertently passed between the rollers simultaneously. It will be readily apparent that where the thickness of a paper bill is used to control the operation of the machine, any lost motion whatsoever will result in inaccuracies and faulty operation.

The object of the present invention is to provide a simple, effective device for holding the bearing and shaft in close contact, so that no lost motion will result from bearing misfit.

Another object of the invention is to provide such a device which will accomplish its purpose without affecting the free movement of the control device with which it is associated.

Still another object is to provide a bearing play-remover which is self-adjusting to compensate for additional bearing wear due to continued use of the machine.

Other objects of the invention will become apparent from the following detailed description of one embodiment of the invention when taken in conjunction with the drawings which accompany and become a part of this specification.

In the drawings:

Figure 1 is a fragmentary vertical section through the upper forward part of a currency counting and sorting machine showing the control lever and the invention in association therewith;

2

Figure 2 is a horizontal section taken on the line 2—2 of Figure 1 showing the control lever and the device of the present invention in plan;

Figure 3 is a vertical section taken on the line 3—3 of Figure 2 showing the cooperative relationship of the control lever, its pivot shaft and the bearing play-remover; and,

Figure 4 is a vertical transverse section taken on the line 4—4 of Figure 3.

To illustrate the application of the present invention and its utility, the invention has been shown in connection with a currency counting and sorting machine of that type disclosed in Patent No. 2,429,159. That machine comprises a plurality of compartments into which paper currency is deposited. The machine is designed to count the bills as they pass into the compartments and to detect the presence of two or more bills inadvertently fed to the machine at one time.

To carry out this operation, the machine employs a pair of feed rollers at each compartment, the rollers comprising a lower driven roller 1 mounted upon a drive shaft 2 which is driven by means of the belt 3 from a convenient source of power (not shown). The roller 1 has rotative movement only and is not movable bodily. At the entrance to each compartment above the roller 1, there is a movable roller 4 carried by a pivoted control lever 5. The control lever is mounted upon a pivot shaft 6 which is carried by a suitable mounting bracket 7 secured to a portion of the machine frame. For purposes of illustration only, the mounting bracket is shown as being a bifurcated member, with the pivot pin 6 passing through both of the depending legs of the member, and the lever 5 being mounted upon the pivot pin between the depending portions of the mounting bracket. The pivot pin is shown as being fixed with respect to the mounting bracket, being held against movement by means of the set screws 8. The lever 5 is freely swingable upon the pin 6. The present design of the control lever calls for the roller 4 being mounted between depending legs 9, which legs extend downwardly from opposite sides of the lever, intermediate the pivotal point and the free end of the lever.

Near the free end of the lever, there is an adjusting screw 10 which contacts an abutment 11 on the machine to limit the downward movement of the lever, so that the rollers 1 and 4 may be held out of engagement and there will be no rotation of the upper roller until a bill is inserted between the rollers. The portion of the lever where movement is critical is the extreme

free end where the adjustable switch actuating stud 12 is located. Upward movement of the lever about its pivot 6 causes the stud 12 to strike the actuating button of a microswitch 13, to close certain circuits and operate the compartment piece counter and the totalizer of the machine in the manner set forth in the patent mentioned above.

Thus it will be seen that the lifting force is applied to the lever midway between its pivot and its free end; that the point of critical movement of the lever is its free end; and the amount of movement which the lever has is extremely small. If there is any play whatever in the pivot bearing, the lever reacts in either of two ways: It may move upward bodily without pivotal movement until the play has been taken out of the bearing and the periphery of the pivot pin opening in the lever contacts the pivot pin, whereupon the lever will begin to rock, or, it may rock at the outset until the stud 12 contacts the actuator button of the micro-switch 13, and then the pivoted end of the lever moves upward to take out the play. In either event, the movement of the free end of the lever is reduced, and there is likelihood that the resultant movement will be insufficient to actuate the switch, and therefore the piece counter and totalizer will fail to make the proper count.

To forestall this possible faulty operation of the machine due to an original misfit in the bearing or looseness as a result of wear, the present invention provides means to exert a force in opposite directions upon the lever and the pivot pin to maintain the surfaces of the bearing opening in the lever and the pivot pin in constant contact. It will be obvious from the complete disclosure that this force may be applied in many ways, and that if the pivot pin is fixed with respect to the lever and movable in the mounting bracket, the invention may be practiced equally well by applying the force between the pivot pin and the mounting bracket.

For purposes of illustration, one practical embodiment of the invention has been shown in the drawings wherein a leaf spring 14 is used to apply a downward pressure upon a pin 15 to hold the pin in contact with the pivot pin. Leaf spring 14 is attached to the upper surface of the lever 5, and for purposes of convenience, it is shown as being bifurcated at its secured end so as to straddle the double bill actuating stud 16. The leaf spring is fastened to the lever by means of the screws 17. Contact pin 15 slips into a vertical opening 18, formed in the lever 5 directly above the opening 19 which receives the pivot pin. Pin 15 is slightly longer than the depth of the opening so that when resting upon the pivot

pin it extends above the upper surface of the lever, causing the leaf spring 14 to be flexed upward and thereby exert a yieldable pressure on the contact pin.

Thus, it will be seen that the pressure of the contact pin on the pivot pin will cause a lifting of the pivoted end of the lever, so that the inner surface of the pivot pin opening, or as shown the bushings mounted therein, will be held in constant contact with the surface of the pivot pin, and no lost motion will result from misfit of the bearing, either as originally made or from wear produced by constant use of the machine. The contact pin has line engagement with the pivot pin, so that its frictional bearing upon the pin as the lever rocks is extremely slight, and the lever, due to its weight will have complete freedom of movement both when lifted by a bill passing between the rollers and when dropping by gravity after the bill has passed through.

With this arrangement, it is unnecessary to provide different mountings for bearings having varying amounts of play, as the play-remover is self-adjusting and will take care of all conditions, and maintain the lever in proper operative position throughout its life.

Although one practical embodiment of the invention has been shown for purposes of illustration, it will be readily apparent to one skilled in the art that the invention may take many forms and is therefore to be limited only by the scope of the appended claim.

What is claimed is:

A play-remover for bearings of precision control devices which include a lever and a pivot pin therefor comprising, an opening in said lever perpendicular to the axis of the pivot pin extending from the surface of the lever to the pivot pin, a contact member in the opening, said contact member being longer than the opening to have one end project beyond the surface of said lever when the other end is in contact with the pivot pin, and a leaf spring attached at one end to the surface of said lever and having its free end yieldably engaging the projecting end of the contact member to exert pressure axially of the contact member against the pivot pin.
